DESIGN FOR A CHAIR

Frederick E. Markus, Belmont, Mass.

Application March 27, 1946, Serial No. 127,984

Term of patent 14 years

(Cl. D15—1)

To all whom it may concern:

Be it known that I, Frederick E. Markus, a citizen of the United States, residing at Belmont, in the county of Middlesex and Commonwealth of Massachusetts, have invented a new, original, and ornamental Design for a Chair, of which the following is a specification, reference being had to the accompanying drawing, forming part thereof.

Fig. 1 is a perspective view;

Fig. 2 is a side elevational view;

Fig. 3 is a plan view; and

Fig. 4 is a bottom perspective view thereof showing my new design.

I claim:

The ornamental design for a chair, as shown.

FREDERICK E. MARKUS.
